UNITED STATES PATENT OFFICE.

RUSSELL I. WILCOX, OF CHICAGO, ILLINOIS, ASSIGNOR TO THE MARQUETTE PIANO COMPANY, OF CHICAGO, ILLINOIS, A CORPORATION OF MICHIGAN.

TUNE-SELECTOR FOR AUTOMATIC PIANOS.

1,398,988.

Specification of Letters Patent.

Patented Dec. 6, 1921.

Application filed July 31, 1918. Serial No. 247,520.

To all whom it may concern:

Be it known that I, RUSSELL I. WILCOX, a citizen of the United States, residing at Chicago, in the county of Cook and State 5 of Illinois, have invented certain new and useful Improvements in Tune-Selectors for Automatic Pianos, of which the following is a specification.

This invention relates to automatic or 10 self-playing pianos of the pneumatic type which are controlled by a perforated music sheet.

The object of the present invention is to provide an instrument capable of playing 15 a plurality of selections on a single sheet or roll and having improved mechanism for selecting and playing any tune on the sheet at will. The present invention may be regarded as an improvement of my former inventions as illustrated and described in patents granted to me, Nos. 1,110,172 dated September 8, 1914, and 1,233,943 dated July 17th, 1917.

By the simple setting of an indicator and 20 starting by means of coin, or otherwise, any selection on the music sheet will be played. The mechanism comprises winding devices which operate in either direction rapidly until the desired selection is reached, after 25 which the selection will be played at a reduced and proper speed. The special object of the present invention is to provide an automatic control valve, which will keep in perfect step with the music roll, and automatically and accurately control the operation 30 of the instrument. This is accomplished by a novel setting mechanism for the dial of the indicator which sets the numbers on said dial in precise cooperative relation with the location of the beginning of 35 the various tunes, or selections, on the music sheet. The automatic valve is geared to the bottom or take-up roll and is connected with a pointer associated with said dial. It is, 40 of course, understood that various tunes have different lengths and that their starting points are not uniformly distributed throughout the length of the sheet. In my improved mechanism the music sheet itself 45 is used to control the operation of the setting mechanism, and hence after being initially set the initial portion of each tune will 50 pass the tracker-bar simultaneously with

the arrival of a valve port at the selected numbers on the dial. A further object is 55 to improve the operation of the instrument in the matter of rotation playing, in which it will play the pieces of music through to the end of the music sheet when not set for selection. A further object is to simplify 60 and perfect the transmission mechanism for driving the music rolls by the motor, in which said rolls may be wound rapidly forward, re-wound rapidly in a reverse direction, and then wound slowly forward to 65 play.

Other objects and advantages of my improved mechanism will be rendered apparent in the following specification when taken in connection with the accompanying drawings, in which

Fig. 38 is a vertical sectional view of the main pneumatic action cut-off valve;

Fig. 39 is a side elevation of the same;

Fig. 40 is a cross-section of the rewind supply box; and

Fig. 41 is a front elevation of the same.

As is usual in machines of this character, they are started by dropping a coin into a suitable receptacle, or may be otherwise started. As the details of this mechanism do not form a part of the present invention they are not shown or described.

By referring to Fig. 1, which is chiefly diagrammatic, it will be seen that I have provided the usual air-motor 1 which is controlled by the throttle valve 2, operated in the usual manner by mechanism not illustrated in the drawings. The tube 3 leads from said motor through said valve to the suction chamber of the valve box 4, in which the usual reduced air pressure is maintained by the exhauster 5 operated by a motor 6. The valve box 4 is ordinarily termed the main pneumatic action cut-off valve, a tube 7 leading from said valve to the main pneumatic action, the details of which are not shown in the drawings as they form no part of my present invention.

The cut-out valve 4 is actuated when a tube 8 leading to its lower chamber 8^a, Fig. 38, is open to air. This condition occurs when the machine is rewinding and when a small flapper valve, (see Figs. 4 and 5) actuated by a shifter pneumatic 16 in the transmission mechanism at 9, Fig. 1, is open. The roll winding mechanism is indicated generally at 10, Fig. 1, and is controlled by an automatic valve 11, said valve forming an important part of my present invention, and being described fully later. At 12 is indicated a primary valve box for controlling various parts of the mechanism. At 13^b is indicated the rewind supply box which by-passes the throttle valve 2 when rewinding occurs and when the full supply of air is needed. A branch tube 13^a leads from the tube 3 to said supply box, and a tube 11^a leads from said supply box directly to the motor. The above may be regarded as an outline of some of the essential parts in an instrument in which my present invention is embodied.

In Fig. 31 is a diagram of some of the essential parts associated with the automatic control valve 11. The main purpose of this control valve is to automatically operate the forward and reverse rewind pneumatics 14, 15 and the shifter pneumatic 16. By rewind herein I mean the winding of the roll which occurs either forwardly or backwardly when not playing. The precise functions of the pneumatics 14, 15 and 16 will be more fully described later, but it may be said for the present that the forward rewind pneumatic 14, when actuated, sets certain gearing in a position to cause the music sheet to be wound forwardly at a fast speed, and the reverse

- rewind pneumatic 15 sets said gearing to cause the music sheet to be wound in the reverse direction at a fast speed. The shifter pneumatic 16, when actuated, will set the gearing to wind the music sheet forwardly at a slower rate of speed to play. The music sheet, portions of which are shown in Fig. 2, is provided with a series of cuttings 17 at the beginning of each selection which pass over 5 the opening 19 in the tracker-bar 10^a. These cuttings, together with the cutting 17^b near the end of the sheet, are the rewind cuttings and control the fast winding of the music sheet in either direction in accordance with 10 15 the relative position of the disks in the control valve 11. The music sheet also is provided with a series of cuttings 17^c near the opposite edge of the sheet, and at the beginning of each selection, which pass over an 20 25 opening 18 in the tracker-bar 10^a. The opening 18 controls the shifter pneumatic 16 which, through mechanism to be later described, throws the gearing into a position which causes it to wind the music sheet slowly forward to play. The music sheet also is provided with a single independent cutting 17^d at the very end which passes over an opening 19^a in the tracker-bar, said opening being so connected as to operate the 30 35 reverse pneumatic 15 when the control valve 11 has been cut out of action by means which will be described later. The music sheet also contains a cutting 17^e at its beginning which passes over an opening 18^a in the tracker-bar, said opening operating the shifter pneumatic 16 to set said gearing to wind said music sheet slowly forward to play, after which all of the selections on the music sheet will be played in rotation. It will therefore 40 45 50 be seen that my improved instrument will be operated by what may be termed four sets of cuttings in the music sheet, these cuttings being numbered, first, 17 and 17^b, which serve as the automatic rewind cutting; second, the independent rewind cutting 17^d, which starts the reverse rewinding of the sheet when the automatic control valve has been cut out; third, the cuttings 17^e, which control the forward slow speed of the sheet when the automatic control valve is in action; fourth, the single cutting 17^e at the beginning of the sheet which starts the sheet forwardly at slow speed when the automatic control valve has been cut out. Cuttings 17^c and 17^d are used on nearly all automatic pianos, so that this system uses only two extra cuttings 17^c, and 17—17^b. Attention is directed to the four cuttings in the music sheet in this manner in order that the operation of the mechanism may be more easily understood when later described. Again, speaking generally, it may be mentioned that these cuttings in the music sheet may be divided into two groups, for convenience, one of the groups 60 65 70 75 80 85 90 95 100 105 110 115 120 125 130 135 140 145 150 155 160 165 170 175 180 185 190 195 198 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945
- tomatic selection of the tunes to be played, while the other group 17^d, 17^e control the rewind and shifting mechanism when the automatic control valve is cut out and the machine is playing in rotation. Referring again to these four lines of cuttings in the music sheet, it will be seen that they control the entire operation of the machine by means of openings 18, 18^a, 19, 19^a.
- Taking first the opening 18, it will be seen to be connected by means of the tube 20 to a cut-out box 21 (to be described later), then by the tube 22 to a port, or aperture, 23 in the forward disk 24 (Fig. 9) of the automatic control valve 11. This disk 24 is fixed to a shaft 25, to which is also fixed the setting knob or handle 26. The port 23 is made to register with a corresponding port 27, when they are brought together in the operation of the instrument, 85 in the rear disk 28. This disk 28 is rotatably mounted upon its supports and is driven by a gear 29, which in turn is driven by a worm 30 on the shaft 31. This shaft 31 carries a gear 32 which meshes with and is driven by a pinion 33 fixed to the shaft 34 of the lower winding roll 35. The gear 32 is yieldably mounted on the shaft 31 by means of a friction disk 36 against which said gear is pressed by a spring 37. The friction disk 36 will be understood to be fixed to the shaft 31.
- The port 27, in the disk 28, communicates through the tube 38 with the particular valve mechanism in the primary box 12, 100 which controls the exhausting of air from the tube 39 leading to the shifter pneumatic 16. The valve mechanism in the primary box 12 is similar to that commonly employed in pneumatic pianos and will be briefly described later.
- The opening 19 in the tracker-bar is connected, by the tube 40, the cut-out box 21, and tube 41, to a port, or passage, 42, in the forward disk 24 of the automatic control valve 11. This port is made to open into either of two semi-circular channels 45 or 45^a in the rear disk 28 of said control valve. Either one of these channels may be connected with the port 42, depending upon the position of the disk 24 as set by the setting knob 26. The channel 45 is connected by means of the opening 43 and the tube 46 with the particular valve mechanism in the primary box 12, which controls the exhausting of air through the tube 47 from the reverse rewinding pneumatic 15. The channel 45^a is connected through the opening 44 and tube 48 to similar valve mechanism in the primary box 12, which controls the exhaustion of air through the tube 49 from the forward rewind pneumatic 14.
- The primary box 12 comprises diaphragms 50 in the lower part of the suction

chamber 51 which latter is connected through the tube 52 to the main suction supply. The diaphragm 50 controls the position of the valve 53 which is connected by means of the channel 55 and tube 47^a to the particular pneumatic to which it may be connected.

It will be seen that the automatic valve 11 comprises two disks, one of them 28 having a movement corresponding with the movement of the music sheet, while the other 24 has a position determined by the operator when setting the instrument to play a desired selection. This setting is made by turning the handle 26, which moves a pointer 60 around a dial 69. The pointer 60 is carried by a hub 61 which is secured to the shaft 25 by a set-screw 62. The dial comprises a disk 63 mounted on the shaft 25 and held against rotation by a pin 64 which engages an arm 65 supporting the forward portion of the control valve. This arm is secured to the frame of the winding roll mechanism at 70. The disk 63 has a groove 66 in its periphery, in which are fitted numbered blocks or segments 67, and which are retained in said groove by a band 68 secured at 71 and 72 to said disk 63. The spring 73, recessed in said block, presses the block radially inward. The disk 24 carries a pin 74 which strikes a stop element 75 when the disk is rotated in one direction, and the tube connections or sleeves 76 strike the stop when the disk is rotated in the opposite direction. The stop 75 will therefore be seen to limit the movement of the pointer 60 in either direction. The stop element 75 is looped around the shaft 25 at 77 and is caused to frictionally engage said shaft by a screw 78. This frictional engagement prevents looseness of the shaft 25 and retains the pointer 60 in any position in which it may be set.

The shaft 25 also carries a cut-out valve disk 79 which is secured thereto by the set screw 80. This cut-out valve disk is concentrically mounted within a second, or outer, disk 81, said latter disk being provided with a pin or arm 82 which is engaged by two small pins 82^a and 82^b on the rear face of the dial block numbered 10. The rotative position therefore of the disk 81 is determined by the position of the dial block 10. In the inner face of the disk 81 is a valve opening 83 communicating with a tube 84 leading eventually to and controlling the cut-out block 21 through tubes 87 and 88. The said cut-out block has the purpose of cutting out the entire automatic control valve when the last tune on the music sheet has been played. The valve port 83 is covered and uncovered by a flange 85 on the disk 79, said flange being segmental, as shown in Fig. 16. One of the radial edges 86 of said flange opens and closes the port

83, as the case may be, depending upon the relative positions of the disks 79 and 81. The disk 79 is so set upon the shaft 25 that it will cover the port 83 shortly after the last tune (No. 10) has started to play. 70

The cut-out block 21 comprises a front or main body 90, to the back of which is secured a hollow member 90^a. The chamber 89 in said member is connected with its respective controlling members in the primary 75 box 12 by a tube 88. Between the pieces 90 and 90^a is a flexible sheet or diaphragm 91 securedly glued around the edges. The block 90 receives the ends of the tubes 40 and 41 which open at their inner ends at 80 the inner face of the block 90, and are therefore closed by the diaphragm 91 when suction in the chamber 89 is removed, and air permitted to flow therein.

When the automatic control valve has 85 been cut out of action, by the cut-out block 21, suction through tube 88 being cut off by the flange 85, the cuttings 17, 17^b and 17^c in the music sheet are no longer capable of controlling the operation of the machine, 90 and the cuttings 17^d and 17^e are then brought into action. These latter cuttings register with the openings 18^a and 19^a. The opening 18^a is connected by the tube 18^b with the tube 38 at 18^c, this tube leading to the 95 particular valve mechanism in the primary box 12 which controls the suction in the tube 39 leading to the shifter pneumatic 16. The opening 19^a is connected by the tube 19^b with the tube 46, a T-joint for that purpose 100 being made at 19^c. The tube 46 leads to the particular valve mechanism in the primary box 12 which controls the reverse rewind pneumatic 15. It will be seen therefore that when the entire automatic control valve 105 mechanism is cut out that the openings 18^a and 19^a control the operation of the shifter pneumatic 16 and the reverse rewind pneumatic 15, respectively. In this condition of the instrument, the tunes on the 110 music sheet will be played in rotation until the end is reached, when the independent rewind cutting 17^d will come into communication with the opening 19^a.

In order that the automatic rewinds may 115 be kept out of operation during rotation playing, from the selected tune to the end, the two disks 24 and 28 are made to travel together by the following means. The disk 28 carries a flat spring 92 secured by screws 120 92^a, said spring having a beveled or inclined end 93 which is adapted to engage a shoulder 94 on the disk 24. This engagement will be strong enough to cause one disk to drive the other, but will allow a setting of the disk 125 24 when selecting a tune in the tune selecting operations. The notch at 94^a, back of the shoulder 94, is cut away on a gradual slope in order to permit the rear disk 28 to rotate in continued rotation playing with 130

out disturbing the forward disk 24. During this simultaneous movement the bridge 28^a lies over and cuts off the port 42.

In order that the movement of the disk 28 may be in unison with the movement of the music sheet while said sheet increases in speed, due to its being wound upon itself upon the lower roll, I have provided an eccentric mounting for the gear 29 which drives said disk 28. An eccentric 99 is provided which is secured by a set screw 100 to a sleeve 103 supported by the arm 101 carried by the main frame. The sleeve 103 receives the reduced portion 102 of the shaft 25, a collar 103^a being secured to said reduced portion to retain the shaft 25 in position. The gear 29 is loosely mounted in a recess at 104 in said eccentric. The disk 28 carries a pin 105 which slides in radial slot 106 in the gear 29. The eccentric position of the gear will cause a gradually increasing speed in the disk by changing the radial position of the pin in the slot. This enables me to drive the disks at a relatively slow speed when the roll is starting and more turns on the winding roll represent one tune so that the disk 28 moves the same distance approximately for each tune assuming the same length of the roll per tune. The gear wheel is limited in its movement in either direction by pins 95 and 96 which engage pins 97 and 98, respectively, in collars on the drive shaft 30.

It is, of course, necessary to reset the numbered blocks 67 on the dial when a new roll is placed in the machine. I perform this resetting automatically in my improved mechanism by making the cuttings in the music sheet itself perform this duty. The series of rewinding cuttings 17-17^b are used for this purpose and are operatively connected with a small resetting pneumatic 111 by the small cut-in valve 86^a, to be described further presently. This small resetting pneumatic 111 actuates a resetting bar 108 which is mounted, by radial arms 109, 109^a, loosely on the shaft 25. This mounting permits both a rotational and longitudinal movement. An arm 112 secured to the movable member of the pneumatic is adapted to engage the arm 109^a and produce a longitudinal movement of the setting bar every time a rewind cutting 17 passes the opening 19 in the tracker bar. The bar 108 is provided with a reduced portion, or lug, 110 at its end which engages small pins 67^a on the rear faces of said blocks. The bar 108 is driven in a rotary direction by the pin 113 secured to the disk 28 and working in a slot 114 in said bar. A spring 115, secured to said pin at one end and at the other end to the arm carrying said bar, produces a constant tendency in said bar to move forwardly into engagement with the pins 67^a. A small latch 116, secured to the

bar 108 and provided with an aperture 117, engages the pin 113 in its rearmost position and holds the bar 108 back until it has been released by hand.

The bar 108 carries a downwardly projecting arm 118, which is adapted to engage a flange 119 and prevent the latch 116 engaging the pin 113, except at such times as when the resetting arm 108 is at the end of its rotary movement. The flange 119 has a limited length, as shown clearly in Figs. 15, 17 and 18. It will be observed that the end 120 of said flange has a position not far removed from the pin or arm 82 in the valve disk 81. The pin 82 has a position between the two pins 82^a and 82^b on the rear of the 10 dial block. The dial block 10 will therefore be seen to determine the position of the valve disk 81 and therefore to determine the position of the end 120 of said flange. The 85 ending of said flange at this point will permit the resetting bar 108 to move back far enough to become latched upon the pin 113 when the resetting bar has reached the 10 dial block in the resetting operations, as will 90 be described later when describing the operation of my instrument in detail. In like manner, the flange 119 is limited at its other end 121 to a certain length, in order to permit the forward movement of the resetting 95 bar 108 into operative relation to the dial blocks during the resetting operation. The position of the edge 121 is so placed that it prevents the return and latching of the resetting bar 108 immediately after the instrument has been started and the disk 28 100 has begun to produce a rotary motion in said resetting bar. The position of the edge 120, however, is determined by the position of dial block 10 regardless of where said dial 105 block may be. The width of said dial blocks 67, in the circumferential direction, is, of course, made less than the movement of the pointer will be for any tune of short length on the music sheet.

The pneumatic 111 is connected with the tube 49 leading to the forward rewind pneumatic 14 by the cut-in valve 86^a, heretofore mentioned. This valve 86^a is provided with two series of ports, one of which series is 115 used for cutting in said pneumatic, this series of ports being shown in section in Figs. 32 and 33. A tube 122 leads from the pneumatic to a channel 123 in the valve casing, and is connected to a channel 124 leading 120 to a tube 125, and thence to the tube 49, which leads to the forward rewind pneumatic 14. The port, or channel, 126 in the rotary member 86^b in said valve connects said tubes 122 and 125 when said pneumatic 125 is put into operation for initial setting (see Fig. 33). The said channel 123 connects the tube 122 with an outlet port 127 when said pneumatic is cut out of action and hence the connection with said tube 125 is cut off (see 130

Fig. 32). The valve member 86^b is provided with a handle or knob 128. When said pneumatic is cut in, as above described, it is in operative relation to the opening 19 in the tracker-bar. The valve 86^a is made to keep the cut out block 21 open by connecting the tube 87 with the outside air, as shown in Fig. 35. Figs. 34 and 35 are sectional views of the valve 86^a, showing said valve in two positions identical with the positions shown in Figs. 32 and 33, respectively. In the upper position, Fig. 34, the tube 84 is connected with the tube 87 in order that the cut-out valve 86^a will not affect the tune 10 selecting control valve 11. But in the resetting position shown in Figs. 35 and 33, the automatic control is cut in to permit the pneumatic 111 to be actuated by the impulses imparted to the forwardly winding 15 pneumatic 14 in the following manner: The port 86^c connecting with the tube 87 permits air to flow to box 12, whereupon the tube 88 will transmit suction to the cut-out box 21, throwing the tracker-bar opening 20 19 through the tube 40 into communication with the tube 41. Previous to initial setting, the pointer 60 is moved to the farthest limit beyond the block 10, which insures 25 communication of the tube 41 through the port 42 with the tube 48 through the medium of the port 44 and groove 45^a. The tube 48 controls communication with the pneumatic 111 through the tube 125, through control box 12 and tube 49. It will thus be obvious 30 that when the forward rewind cuttings pass over the tracker-bar opening 19 impulses will be transmitted to the pneumatic 111 as well as the pneumatic 14, which latter merely functions without effect. As mentioned 35 above, the forward valve disk 24 is moved to the extreme right in order that the port 42 may be in constant communication with the forward rewind channel 45^a in the rear valve disk 28 during the resetting 40 operations.

The music sheet is wound upon the usual rollers 35 and 129 carried by the shafts 34 and 130, respectively. Secured to one end of the shaft 130 is a gear 131, and secured to 45 the shaft 34 is a similar gear 132. An idler gear 133 is mounted upon a stub shaft 134 secured to the frame and meshes with the lower side of the gear 131. A suitable gear 135, driven by the motor, is secured to the 50 short shaft 140 carried by the swinging arm 141. The shaft 140 is attached to and driven by a shaft 136 by a suitable ball or universal joint 137, and the shaft 136 is in turn attached to and driven by the shaft 55 139 of the motor 1 by a universal joint comprising a flexible leather washer 138.

This swinging arm 141 is pivotally mounted at 142 upon a stub shaft 143 secured at 143^a to the frame of the music roll mechanism. The swinging arm 141 is actuated

by an arm 144 rigidly secured to it, (see Fig. 4) said arm 144 being in turn actuated in one direction or the other by the rewind pneumatics 14—15, by means of the intermediate reciprocating rod 144^c having a bent end 144^d and a coacting nut 144^e engaging said arm 144, as shown in Figs. 25 and 26.

The swinging arm 141 may be retained in either of its two extreme positions, as will be described below, in which positions the gear 135 may be meshed with either the gear 132 or the idler gear 133. When it is in mesh with the gear 132 the lower roll will, of course, be driven in a manner to cause a forward winding of the music sheet, and when it is in mesh with the idler gear 133, the gear 131 will clearly be driven in the opposite direction to cause a reverse winding of the music sheet.

The means for retaining the arm 141 in either position consists of the roller 146 carried by a lever 149, which roller is adapted to bear upon the inclined faces 147 and 148 at the end of such arm, (see Figs. 28 and 4). The lever is pivotally mounted at 150, and is pulled to the right at its upper end by a spring 151, which is secured to a suitable support or anchorage 152. The tension of the spring 151 will therefore be seen to be the means of retaining the arm in either position. The spring, however, is weak enough to permit the rewind pneumatics 14—15 to overcome its tension when wedging the roller away from the ends of the lever when the arm 141 swings in either direction.

In the preceding mechanism, provision has been made for winding the music sheet in either direction at a high speed. It is, of course, desirable to wind the music sheet forwardly at a low speed while the instrument is playing a tune. The gearing for this purpose comprises a small pinion 156 on the shaft 140 which is adapted to mesh with and drive an internal gear 157 rotatably mounted upon the stub shaft 158. This latter shaft is carried by a second swinging arm 159 which is pivotally mounted upon the stub shaft 143 adjacent the first swinging arm 141. Secured to the hub of the internal gear 157 is a spur gear 160 which meshes with a large gear 161 secured to the shaft 34 of the lower roll. The above train of gearing, comprising the pinion 156, internal gear 157, pinion 160 and gear 161, forms a low speed gearing for driving the shaft 34 forwardly at a proper speed to play the tune. This latter gearing is moved into operative relation with said lower gear 161 by a coil spring 162^b. The arm 159 is pulled downwardly by the coil spring attached to the arm 159 at 162^a, the other end of which is attached to a pin projecting from the music roll frame at 162^c, about two inches below and is stopped by a pin 165 projecting from the frame through the slot 162^d in the

arm 159. A pin 164 also projects from the inside wing of the arm 141 into the slot 162^c of the arm 159, (see Figs. 26 and 27). The spring 162 presses under the pin 164 secured 5 to the arm 141, the other end of which spring is resisted by resting on top of the arm 159 at 162^c. If the shifter pneumatic 16 collapses so as to push the lever 149, by the rod 154 engaging the lever 149 at 154^a, 10 to the left, so that its roller 146 will not interfere, then the lever 141 will obviously fly into a mid-position, that is where the prong 166 is resting on the pin 165 and where the pin 164 is resting upwardly on a 15 prong 167. This is the playing position in which the pinion 156 meshes with the internal gear 157 and where the pinion 160 meshes with the large gear 161. The spring 162^b has a tendency to retain the parts in 20 the playing position because of its downward pull on the lever 159.

The shifter pneumatic is also adapted to operate a small valve 168 which covers and uncovers two ports 169 and 170 in the valve block 171. The valve 168 is pushed open by the rod 154 when the pneumatic 16 is opened by the tension of the spring 151 and the suction within said pneumatic is removed. When the pneumatic 16 is actuated, or 30 closed, the elasticity of the valve member 168 causes it to close upon the two ports 169 and 170. This valve has been referred to before as controlling the operations of the valve box 4 and the rewind supply box 13^b. 35 When said valve 168 is open, pressure is admitted to the lower chamber 8^a through the tube 8, the diaphragm 8^b being adapted to lift and cause the valve 172 to close the aperture 173. This aperture leads from the 40 suction chamber 174 to the chamber 175, and thence through the tube 7 to the main pneumatic action, not shown in the drawings. The outlet valve 176 is carried by the same stem 177 as carried the valve 172, and the 45 outlet 178 leads from the chamber 175 to the outside air, thereby relieving the pressure in the main action pneumatics when this cut-out valve is operated. A bleed passage 179 and the small bleed aperture 180 permit the suction to reach into the lower 50 chamber 8^a and pull down the diaphragm when the small valve port 169 is closed. In a similar manner the valve 168 opens and closes the port 170, open to the tube 13, and 55 leading to the lower chamber 181 of the rewind supply box 13^b. When said port is open, the pressure in the said chamber raises the diaphragm 182 and opens the valve 183, thus causing the suction chamber to be 60 opened to the tube 11^a leading to the air motor 1. The bleed passage 185, controlled by the screw 186, permits suction to be restored in the chamber 182 when the valve 65 is closed. The suction chamber is connected with the suction chamber 174 of the valve 70 box 4 (Fig. 38) by the small tube 13^a, which is joined to the tube 3 at 13^c, the latter tube leading to said valve box. The purpose of the above is to throw full suction effect on the motor 1, eliminating throttling by the 75 box 2 and causing full speed. The chamber 174 will be seen to be connected with the main exhauster 5 by the tube 5^a in the usual manner.

In order to provide means for manually 75 adjusting the gearing which connects the air motor with the music rolls 35 and 129, I provide a small lever 187 pivotally attached at 188 to the frame and having a lug 189 at its inner end which engages the upper 80 tongue 166 of the lever 159 and permits the operator to raise said lever and disconnect the gearing from the bottom roll; this permits the rolls to be operated manually.

The operation of my improved mechanism 85 has been largely referred to in the foregoing description, but the following outline of its use in practice is added. Assuming that the dial blocks 67 have been properly set, the pointer 60 is moved to the number selected, the handle or knob 26 being used for that purpose. Supposing the number 5 has been selected and that the pointer previously had a position at the right end of the dial, i. e. from 6 to 10, the setting movement of 90 the pointer would cause the forward disk 24 to move to the left. This movement will cause the valve port 42 to come into communication with the semi-circular channel 45 in the rear valve disk 28, (see Fig. 10, 95 for example). Communication will then be made from the tracker-bar opening 19 through the tube 40, cut-out block 21, tube 41, opening 42, channel 45, opening 43, and tube 46 to the primary box 12 (see Fig. 31). 100 This will operate the particular valve mechanism in said primary box which admits suction to the tube 47 leading to the reverse 105 rewind pneumatic 15. This reverse pneumatic will then close upon passage of cuttings 17 or 17^b over the tracker-bar opening 19 and operate the lever 144 to throw the lever 141 to a position in which the gear 135 will mesh with the idler 133. The idler in turn will drive the gear 131 and cause a 110 rapid rewinding movement of the music sheet. The rewinding will continue until the valve opening 27 in the rear disk, driven by the worm 30, reaches the valve opening 23 in the forward disk, when the shifter 115 pneumatic opening 18 in the tracker-bar will be in operative relation with the shifter pneumatic 16. This operative relation will comprise the connection through said opening 18, the tube 20, cut-out block 21, tube 120 22, opening 23 in the forward disk, opening 27 in the rear disk, tube 38, and the particular valve mechanism in the primary box 12, which controls the suction in the tube 39 125 leading to the shifter pneumatic 16. The 130

shifter pneumatic 16 will then be closed by the suction and will cause a forward push upon the rod 154, which will tilt the lever 149 into such a position that the roller 146 5 will allow the lever 141 to assume an intermediate position. This intermediate position will be due to the downward tension of the spring 162^b which draws the lever 159 against the pin 165 at 165^a. The upward 10 pressure of the spring 162 on the pin 164 will hold the gear 135 out of mesh with the gear 132, but will mesh the pinion 156 with the internal gear 157 for playing drive. In 15 said position the gear 135 will have moved downwardly out of mesh with the idler 133. At the same time the gear 160 will be allowed to engage the gear 161. The motor will then be free to drive the music sheet forwardly through the pinion 156, internal 20 gear 157 and said gears 160 and 161. The mechanism will then be in condition to wind the sheet slowly forward to play. Simultaneously with the connection of the openings 23 and 27 in the two disks of the control 25 valve, the valve opening 42 in the forward disk will reach the blank space 28^a on the rear disk, and further operation of the rewinding mechanism will be prevented. At the same time, the yielding spring 93 will engage 30 the shoulder 94, and the rear disk will drive the forward disk forwardly until the tune has been completed, whereupon the usual stop mechanism will cause the machine to stop playing, if a coin actuated machine 35 or if extra coins have been inserted, the machine will play on in rotation.

For a further example, suppose that we now set the pointer at number 8 on the dial before tune 5 has been passed—the valve 40 opening 42 in the forward disk will then be moved to a position in connection with the forward rewind channel 45^a, and the forward rewind pneumatic 14 will be actuated in a manner similar to that described in connection 45 with the reverse pneumatic 15 in the preceding example. In this example, however, the operation is slightly different in the matter of the spring 93, which is forced over the shoulder 94 in the operation of setting. During the automatic rewinding, the rear disk 28 moves to a position in which the spring 93 again engages the shoulder 94 and in which bridge 28^a closes the port 42.

Should it be desired to play the next tune 55 on the music sheet without selecting any particular one, it is merely necessary to start the machine, whereupon the said tune will be played, the rear disk 28 driving the forward disk 24 by means of the spring 93. In 60 like manner, the remainder of the tunes on the music sheet may be played in rotation to the end of the sheet. When reaching the end, the pointer will have passed the block numbered 10. At this time the cut-out valve 65 85 closes the opening 83 leading to the tube

84, and the entire automatic control valve 11 is cut out of action. This is due to the suction being established in the tube 84 leading through the valve 86^a, and the tube 87, to the particular valve mechanism in the primary 70 box 12, which cuts off suction in the tube 88 and cut-out block 21. The pressure enters the chamber 89 in said block and causes the diaphragm 91 to close the openings leading to the tubes 40, 41, 20 and 22. When thus 75 closed, it is clear that no further action can occur in the automatic control valve 11.

After the automatic control valve 11, however, has been cut out, as above described, the tunes on the music sheet can be played 80 in rotation from beginning to end, and repeated. When reaching the end, the independent rewind cutting 17^a comes into communication with the opening 19^a in the tracker-bar and through the tube 19^b and 85 tube 46, the particular valve mechanism in the primary box 12 is operated which opens the suction to the tube 47, thereby operating the reverse pneumatic 15. Through the mechanism previously described, the music 90 sheet is rewound back to the beginning until the independent cutting 17^a on the music sheet opens into the tracker-bar at 18^a. The forward playing mechanism is then actuated, the connection then being through the tube 18^b to the juncture 18^c with the tube 38 and then to the particular valve mechanism in the primary box 12 which controls the suction in the tube 39, leading to the shifter pneumatic 16, which actuates the lever 149 and meshes the gears as described above. The forward playing of the music sheet then occurs and the first tune is played until the stop mechanism at the end of said tune stops the machine. The insertion of 100 another coin in the slot mechanism, or otherwise starting the machine, causes the music sheet to continue its movement in the forward direction until the second tune has been played in the same manner. In this 110 manner all the tunes on the music sheet may be played in rotation repeatedly until the automatic control valve 11 has been again put into action. This is accomplished by simply setting the pointer 60 to the desired 115 number on the dial, whereupon the selected tune will be played in the manner previously described.

When it is desired to insert and play a new music sheet, it is necessary to set the 120 numbers on the dial, so that their relative spacing will correspond to the lengths of the tunes on the music sheet. This is necessary in order that the operation of the tune selecting mechanism may perform its function 125 accurately, and keep in step with the tunes on the music sheet. Assuming that the previous sheet has been reversely wound onto the upper roll and that the rewinding movement of said upper roll has caused the 130

rear disk 28 to be moved as far to the left as it will go, the new roll is inserted in place with its end engaging the lower roll. The pointer is then turned to the right as far as it will go. This position of the pointer causes the valve opening 42 in the forward disk to be in communication with the semicircular channel 45^a in the rear disk, and to remain in connection therewith throughout the entire movement of the rear disk to the right in the following operation of resetting.

The cut-in valve 86^a is then rotated by means of the handle 128 until said valve has the positions illustrated in Figs. 33 and 35. The setting pneumatic 111 is thus placed in operative connection with the tube 49 leading to the forward rewind pneumatic 14. When this connection is established, it is clear that the pneumatic 111 will operate every time that the pneumatic 14 operates, and the pneumatic 14, is, of course, operated by the cuttings 17 when they pass over the opening 19 in the tracker-bar. When the valve 86^a is set, as above described, the cut-out block 21 will then be open, since the opening 86^c admits air to the tube 87, which will permit communication between the tracker-bar opening 19 and the opening 42 in the forward disk and channel 45^a in the rear disk through the tubes leading thereto and to the primary box 12 controlling the suction in the tube 49.

The segment blocks in the dial are then all pushed to the left by hand as far as they will go. Then they will, of course, be in contact with each other. The small lever 187 may then be operated to place the transmission gearing into operative relation with the forward winding roll. The latch 116 is then released from the pin 113, whereupon the spring 115 will throw the resetting bar 108 forward until the reduced end or lug 110 on said bar comes into operative relation with the pins 67^a on the dial blocks. The machine is then started and the music sheet is wound forwardly until the first cutting 17 reaches the opening 19^a in the tracker-bar, when the bar 108 will be moved backwardly by the pneumatic 111. During this time, the said bar is being moved toward the right because of its connection with the disk 128 by the pin 113. This initial rotary motion, caused by the winding of the music sheet, causes it to push the first dial block forwardly a short distance until the first cutting 17 pulls the bar 108 back. The backward movement is now limited by the flange 119. When the cutting has passed the tracker-bar opening 19^a, the pneumatic 111 will, of course, be open and the bar 108 will be free to move forwardly again, but in the meantime it has advanced far enough to the right to engage the end of the pin on the first dial block, and it will slide along

said pin because of its rotary motion until it drops behind it. After the bar has passed the first pin, as above described, its rotary motion to the right causes it to engage the second pin, and, in like manner, each of the following pins until they are all placed in positions corresponding exactly with the variable spaces between the cuttings 17 on the music sheet. When the last dial block 10 has been positioned, the small arm 118 on the resetting bar is free to pass beyond the flange 119, thereby allowing the resetting bar 108 to move rearwardly to a position where the latch 116 engages the pin 113. Previous to this time, during the resetting operations the rearward motion of the bar 108 was limited by the flange 119 in each backward movement thereof, and the initial portion of said flange 119 prevented the backward movement of said bar after the setting of the first block had been accomplished, this being due to the slight rotary movement which thereupon occurred. After the resetting of the dial blocks has been completed, as above described, the valve 86^a is restored to its normal position, such normal position being illustrated more especially in Figs. 32 and 34, whereupon the automatic selective control valve 11 is restored to its normal operative connections.

I do not wish to be restricted to the specific embodiment shown in the drawings and described above, except as described in the appended claims.

What I claim is:

1. In an automatic piano, the combination with a perforated music sheet having a plurality of separate selections, of winding drums for winding said sheet in either of two opposite directions, means for operating said drums to wind said sheet forwardly or backwardly, and selective controlling means for said operating means comprising relatively movable coöperative members, one of said members being set by hand to determine the selection to be played, and the other member being operatively connected with said music sheet for continuous rotation to move said second member into operative relation with said first member to permit the desired selection to be played.
2. In an automatic piano, the combination with a perforated music sheet having a plurality of separate selections, of winding drums for winding said sheet in either of two opposite directions, means for operating said drums to wind said sheet forwardly or backwardly, and pneumatic selecting controlling means for said operating means comprising relatively movable coöperative members having ports capable of communication when brought into operative relation, one of said members being set by hand to determine the selection to be played, and the other member being operatively connected

to said music sheet for continuous rotation to move said second member into operative relation with said first member to permit the desired selection to be played.

- 5 3. In an automatic piano, the combination with a perforated music sheet having a plurality of separate selections, of winding drums for winding said sheet in either of two opposite directions, means for operating 10 said drums to wind said sheet forwardly or backwardly, selective controlling means manually adjustable for determining the selection to be played and controlling the movement of said sheet toward the position 15 necessary to play said selections, means for operating said drums to wind said sheet forwardly to play after said position has been reached, said last named means being actuated by said controlling means, means for 20 automatically cutting said selective controlling means out of operative connection with said operating means when the last selection on the sheet has been played, and means for causing said operating means to rewind said 25 sheet to the beginning and play the selections on said sheet in rotation after said selective controlling means has been cut out.

4. In an automatic piano, the combination with a perforated music sheet having a plurality of separate selections, of winding drums for winding said sheet in either of two opposite directions, gear wheels attached to said drums, a shiftable gear wheel, means for driving said shiftable gear wheel, 30 an idler gear wheel meshing with one of said drum gears, means for moving said shiftable gear into operative relation with either said idler gear or with the gear on the other of said winding drums, means for 35 yieldably retaining said shiftable gear in either of said positions, means having a tendency to move said shiftable gear to an intermediate position, and means for retaining said shiftable gear in either of said 40 positions.

5. In an automatic piano, the combination with a perforated music sheet having a plurality of separate selections, of winding drums for winding said sheet in either of 50 two opposite directions, gear wheels attached to said drums, a shiftable gear wheel, means for driving said shiftable gear wheel, an idler gear wheel meshing with one of said drum gears, means for moving said shiftable gear into operative relation with either said idler gear or with the gear on the other of said winding drums, means for yieldably retaining said shiftable gear in either of said 55 positions, means having a tendency to move said shiftable gear to an intermediate position, means for retaining said shiftable gear in either of said positions, and means for removing said retaining means and permitting said shiftable gear to move to said 60 intermediate position.

6. In an automatic piano, in combination with a perforated music sheet having a plurality of separate selections, means for winding said sheet in either of two directions at high speed, pneumatic means for determining 70 the direction in which said sheet is wound, selective controlling means for disconnecting said winding means when the desired selection on said sheet is reached, means for driving said winding means at a slow speed to play the desired selection, pneumatically controlled means for shifting the driving connections to said slow speed driving means and disconnecting said high speed winding means, means for cutting out 80 of action said selective controlling means when the last selection on said sheet has been played, and means independent of said selective controlling means for rewinding said sheet to the beginning thereof and playing 85 said selections in rotation.

7. In an automatic piano, in combination with a perforated music sheet having a plurality of separate selections, means for winding said sheet forwardly at high speed, 90 means for winding said sheet backwardly at high speed, means for winding said sheet forwardly at low speed, a selective controlling valve comprising two coöperative members having coacting surfaces in contact, 95 one of said members being adjustable by hand to a position which determines the selection to be played, the other member being operably connected to said music sheet to continuously rotate said member relatively to said first member, said first member having a port leading to and controlled by said music sheet, said second member having two elongated ports either of which is connectible with said port in said first 100 member, one of said elongated ports being connected with a source of suction supply, a valve mechanism controlling said forward winding means and controlled by said elongated port, the other of said elongated ports 105 being connected with said supply, and a valve mechanism controlling said backward winding means and controlled by said last named elongated port.

8. In an automatic piano, in combination with a perforated music sheet having a plurality of selections, means for driving said sheet forwardly or backwardly at high speed, pneumatic means for determining the direction thereof, and a controlling valve 115 comprising two members having coacting surfaces, one of said members being adjusted by hand to a position determining the selection to be played and having a port leading to and controlled by perforations in 120 said music sheet, the other of said members being operably connected to said music sheet to continuously rotate said member relatively to said first member, said second member having two elongated ports either of 125 130

which may connect with the port in said first member, one of said elongated ports being connected with and actuating said pneumatic means to cause said sheet to move forwardly, the other of said elongated ports being connected with and actuating said pneumatic means to cause said sheet to move backwardly.

9. In an automatic piano, in combination with a perforated music sheet having a plurality of selections, means for driving said sheet forwardly or backwardly at high speed, pneumatic means for determining the direction thereof, a controlling valve comprising two members having coacting surfaces, one of said members being adjusted by hand to a position determining the selection to be played and having a port leading to and controlled by perforations in said music sheet, the other of said members being operably connected to said music sheet to move said member relatively to said first member, said second member having two elongated ports either of which may connect with the port in said first member, one of said elongated ports being connected with and actuating said pneumatic means to cause said sheet to move forwardly, the other of said elongated ports being connected with and actuating said pneumatic means to cause said sheet to move backwardly, said elongated ports terminating at a distance from each other leaving a blank space between equal to or greater than the width of the port in said hand adjusted member, means for driving said sheet and said second valve member at low speed forwardly to play the music selected, and pneumatic means for actuating said slow speed driving means, said pneumatic means being connected with a suction supply when said blank space reaches said port in said hand adjusted element.

10. In an automatic piano, in combination with a perforated music sheet having a plurality of selections, means for driving said sheet forwardly or backwardly at high speed, pneumatic means for determining the direction thereof, a controlling valve comprising two members having coacting surfaces, one of said members being adjusted by hand to a position determining the selection to be played and having a port leading to and controlled by perforations in said music sheet, the other of said members being operably connected to said music sheet to move said member relatively to said first member, said second member having two elongated ports either of which may connect with the port in said first member, one of said elongated ports being connected with and actuating said pneumatic means to cause said sheet to move forwardly, the other of said elongated ports being connected with and actuating said pneumatic means to cause said sheet to move backwardly, said elongated ports terminating at a distance from each other leaving a blank space between equal to or greater than the width of the port in said hand adjusted member, means for driving said sheet and said second valve member at low speed forwardly to play the music selected, said members also having other connecting ports which come into communication when said blank space reaches said first-named port, said last-named ports controlling the suction supply to said low speed pneumatic actuating means, a dial having movable numbered blocks adjustable to spacings corresponding to the relative positions of the beginnings of the respective selections on said sheet, and an indicating pointer rigidly connected with said hand adjusted member and cooperating with said numbered blocks.

gated ports terminating at a distance from each other leaving a blank space between equal to or greater than the width of the port in said hand adjusted member, and pneumatic means for driving said sheet and said second valve member at low speed forwardly to play the music selected, said members also having other connecting ports which come into communication when said blank space reaches said first-named port, said last-named ports controlling the suction supply to said low speed pneumatic actuating means.

11. In an automatic piano, in combination with a perforated music sheet having a plurality of selections, pneumatic means for driving said sheet forwardly or backwardly at high speed, pneumatic means for determining the direction thereof, a controlling valve comprising two members having coacting surfaces, one of said members being adjusted by hand to a position determining the selection to be played and having a port leading to and controlled by perforations in said music sheet, the other of said members being operably connected to said music sheet to move said member relatively to said first member, said second member having two elongated ports either of which may connect with the port in said first member, one of said elongated ports being connected with and actuating said pneumatic means to cause said sheet to move forwardly, the other of said elongated ports being connected with and actuating said pneumatic means to cause said sheet to move backwardly, said elongated ports terminating at a distance from each other leaving a blank space between equal to or greater than the width of the port in said hand adjusted member, means for driving said sheet and said second valve member at low speed forwardly to play the music selected, said members also having other connecting ports which come into communication when said blank space reaches said first-named port, said last-named ports controlling the suction supply to said low speed pneumatic actuating means, a dial having movable numbered blocks adjustable to spacings corresponding to the relative positions of the beginnings of the respective selections on said sheet, and an indicating pointer rigidly connected with said hand adjusted member and cooperating with said numbered blocks.
12. In an automatic piano, in combination with a perforated music sheet having a plurality of selections, means for driving said sheet forwardly or backwardly at high speed, pneumatic means for determining the direction thereof, a controlling valve comprising two members having coacting surfaces, one of said members being adjusted by hand to a position determining the selection to be played and having a port lead-

ing to and controlled by perforations in said music sheet, the other of said members being operably connected to said music sheet to move said member relatively to said first member, said second member having two elongated ports either of which may connected with the port in said first member, one of said elongated ports being connected with and actuating said pneumatic means 10 to cause said sheet to move forwardly, the other of said elongated ports being connected with and actuating said pneumatic means to cause said sheet to move backwardly, said elongated ports terminating at a distance 15 from each other leaving a blank space between equal to or greater than the width of the port in said hand adjusted member, means for driving said sheet and said second valve member at low speed forwardly 20 to play the music selected, said members also having other connecting ports which come into communication when said blank space reaches said first-named port, said last-named ports controlling the suction supply 25 to said low speed pneumatic actuating means, a dial having movable numbered blocks adjustable to spacings corresponding to the relative positions of the beginnings of the respective selections on said sheet, an 30 indicating pointer rigidly connected with said hand adjusted member and coöperating with said numbered blocks, and a cut-out valve mechanism actuated by said control valve member connected with the music sheet, said cut-out mechanism cutting said control valve out of action when said pointer reaches the last number on said dial.

13. In an automatic piano, in combination with a perforated music sheet having a plurality of separate selections and controlling perforations at the beginning of each selection for causing a rapid winding of said sheet forwardly or backwardly, a selective controlling valve operably connected with said music sheet and operated by said perforations for determining the direction of movement of said sheet and its speed after the desired selection has reached its operative position, and means for actuating 40 said sheet and said valve.

14. In an automatic piano, in combination with a perforated music sheet having a plurality of separate selections and controlling perforations at the beginning of each selection for causing a rapid winding of said sheet forwardly or backwardly, a selective controlling valve operably connected with said music sheet and operated by said perforations for determining the direction of movement of said sheet and its speed after the desired selection has reached its operative position, means for actuating said sheet and said valve, and means for cutting said controlling valve out of operative connection 55 when the last selection has been played, such

sheet having additional perforations at each end for causing the winding of the entire sheet in either respective direction independently of said first-named perforations.

15. In an automatic piano, in combination with a perforated music sheet having a plurality of separate selections and additional controlling perforations at the beginning of each selection for causing a rapid winding of said sheet forwardly or backwardly, a selective controlling valve operably connected with said music sheet and operated by said perforations for determining the direction of movement of said sheet and its speed after the desired selection has reached its operative 70 position, and means for actuating said sheet and said valve, said controlling valve having a hand adjusted element associated with a dial, the face of said dial having movable numbered elements representing the selections on said sheet and adjustable to relative positions corresponding to the positions of the beginnings of said selections on said sheet.

16. In an automatic piano, in combination with a perforated music sheet having a plurality of separate selections and additional controlling perforations at the beginning of each selection for causing a rapid winding of said sheet forwardly or backwardly, a selective controlling valve operably connected with said music sheet and operated by said perforations for determining the direction of movement of said sheet and its speed after the desired selection has reached its operative 80 position, said controlling valve having a hand adjusted element associated with a dial, the face of said dial having movable numbered elements representing the selections on said sheet and adjustable to relative positions corresponding to the positions of the beginnings of said selections on said sheet.

17. In an automatic piano, in combination with a perforated music sheet having a plurality of separate selections and additional controlling perforations at the beginning of each selection for causing a rapid winding of said sheet forwardly or backwardly, a selective controlling valve operably connected with said music sheet and operated by said perforations for determining the direction of movement of said sheet and its speed after the desired selection has reached its operative position, said controlling valve having a hand adjusted element associated with a dial, the face of said dial having movable numbered elements representing the selections on said sheet and adjustable to relative positions corresponding to the positions of the beginnings of said selections on said sheet.

the beginnings of said selections on said sheet, said controlling valve having a movable element operably connected to said music sheet for movement in unison therewith, a setting bar for said numbered elements, said bar being actuated by said movable element, pneumatic means controlled by said additional perforations for momentarily moving said bar out of engagement with each successive numbered element to permit it to pass to the next element, and means for causing said bar to return to operative relation to said numbered elements.

18. In an automatic piano, in combination with a perforated music sheet having a plurality of separate selections and additional controlling perforations at the beginning of each selection for causing a rapid winding of said sheet forwardly or backwardly, a selective controlling valve operably connected with said music sheet and operated by said perforations for determining the direction of movement of said sheet and its speed after the desired selection has reached its operative position, said controlling valve having a hand adjusted element associated with a dial, the face of said dial having movable numbered elements representing the selections on said sheet and adjustable to relative positions corresponding to the positions of the beginnings of said selections on said sheet, said controlling valve having a movable element operably connected to said music sheet for movement in unison therewith, a setting bar for said numbered elements, said bar being actuated by said movable element, pneumatic means controlled by said additional perforations for momentarily moving said bar out of engagement with each successive numbered element to permit it to pass to the next element, means for causing said bar to return to operative relation to said numbered elements, means for limiting the movement of said bar under the action of said pneumatic means until the last numbered element has been set, and means for retaining said bar out of operative relation with said numbered elements.

19. In an automatic piano, in combination with a perforated music sheet having a plurality of separate selections and additional controlling perforations located at suitable positions on said sheet, a plurality of indicating members corresponding to the selections on said sheet, and means actuated by said controlling perforations and operable to automatically set said indicating members in position to correspond with the relative location of said selections on said sheet.

20. In an automatic piano, in combination with a perforated music sheet having a plurality of separate selections and additional controlling perforations located at suitable positions on said sheet, a plurality of movably mounted indicating members corre-

sponding to the selections on said sheet, and means actuated by said controlling perforations and operable to automatically set said indicating members in position to correspond with the relative location of said selections on said sheet, said means comprising mechanism actuated in accord with the movement of said music sheet.

21. In an automatic piano, the combination with a perforated music sheet having a plurality of separate selections and additional controlling perforations located at suitable positions on said sheet, a plurality of indicating members corresponding to the selections on said sheet, and means actuated by said controlling perforations and operable to automatically set said indicating members in position to correspond with the relative location of said selections on said sheet, said means comprising mechanism actuated in accord with the movement of said music sheet and also mechanism operable to successively engage said indicating members to locate them.

22. In an automatic piano, the combination with a perforated music sheet having a plurality of separate selections and additional controlling perforations located at suitable positions on said sheet, a plurality of indicating members corresponding to the selections on said sheet, and means actuated by said controlling perforations and operable to automatically set said indicating members in position to correspond with the relative location of said selections on said sheet, said means comprising mechanism actuated in accord with the movement of said music sheet and also mechanism operable to successively engage said indicating members to locate them, said last-named mechanism functioning to disengage said members upon the passage of said controlling perforations over a tracker-bar.

23. In apparatus of the class described, a rotatable drum, selective mechanism comprising a manually rotatable disk, a coacting driven disk, and means operable to yieldingly and operatively engage said driven disk with said normally rotating disk, said last-named means comprising a spring member carried by one of said disks.

24. In apparatus of the class described, a rotatable drum, selective mechanism comprising a manually rotatable disk, a coacting driven disk, and means operable to yieldingly and operatively engage said driven disk with said normally rotating disk, said last-named means comprising a spring member carried by one of said disks, the other of said disks being recessed for engagement by said spring.

In testimony whereof, I have subscribed my name.

RUSSELL I. WILCOX.
